VENDING MACHINE

Albert W. Thoreson, Thief River Falls, Minn.

Application June 13, 1938, Serial No. 213,513

2 Claims. (Cl. 312—59)

My invention relates to vending machines and more particularly to newspaper vending machines.

One of the principal objects of my invention is to provide a newspaper vending machine which is simple in construction, durable in use, efficient in operation and economical in manufacture.

Another object of my invention is to provide a machine of the above described character equipped with means whereby a customer may easily discern whether a newspaper or other periodical is available in the machine for sale.

Other objects and advantages will be apparent from the following description, appended claims and annexed drawings.

Referring to the drawings wherein like reference characters designate like parts throughout the several views:

Figure 1 is a longitudinal sectional view of my invention.

Figures 2 and 3 are sectional views taken on the lines 2—2 and 3—3 of Figure 1 respectively.

Figures 4, 5 and 6 are detail sectional views taken on the lines 4—4, 5—5 and 6—6 of Figure 3 respectively.

Figure 7 is a detail perspective view of the magazine release member.

Figure 8 is a detail sectional view taken on the line 8—8 of Figure 1.

In practicing my invention I provide a housing 5 having an upper arcuate top section 6 and front, rear and side walls 7, 8 and 9 respectively. The side walls are provided with bearings 10 in which are journaled the ends of a rotatable shaft 11 transversing the housing and to which is fixed and rotatable therewith a reel constituting a magazine 12 equipped with sides 13 and 14 connected together by a plurality of radially extending partitions 15 coating with the sides 13 and 14 to form a plurality of pockets 16.

Fixed to the shaft 11 between one of the bearings 10 and side 14 of the magazine is a drum 17 having connected thereto one end of a cable 18. The opposite end of the cable is connected to an elongated cylindrical shaped weight 19 slidably mounted in a guideway or tube 20 fixed to the bottom of the housing as clearly illustrated in Figure 1. The cable is normally wound about the drum 17 and the weight 19 serves to normally urge rotation of the magazine. The sides 13 and 14 are fashioned with a plurality of circumferentially extending spaced slots 21, a pair of said slots being oppositely disposed in the sides of the pocket 16 adjacent the outer periphery of the magazine.

Extending through each pair of said oppositely disposed slots and transversing the magazine is a shaft 22 having rotatably mounted thereon a roller 23 for engagement with a newspaper or the like as hereinafter set forth.

The shaft 22 constitutes a connecting arm of a pair of springs 24 and 25 secured to the sides 13 and 14 respectively adjacent each of the pockets 16. Said springs coat with said shaft 22 to urge the roller 23 in clamping engagement with a newspaper or the like secured against a face of a partition 15 as illustrated in Figure 1. One of the pockets 16 has printed on the partition thereof indicia 26 denoting the word "empty" and said pocket is not provided with a shaft 22 and roller 15 23 although it is to be understood that the same could be equipped with a shaft or roller without interfering with the operation of the device.

Mounted on the side 14 adjacent the outer edge thereof are a plurality of spaced stop members 20 27 having inclined outer faces 28 for a purpose hereinafter set forth. Each of said stop members is arranged adjacent and exteriorly of a respective partition 15.

Secured to the front wall 7 is a coin operated 25 mechanism 29 comprising a guide 30 extending within said housing adjacent the magazine and a slide 31 mounted within said guide and equipped with a finger piece 32 and a coin opening 33. The slide 31 is also fashioned with a slot 34 communicating with the opening 33 and terminating at the inner end of the slide.

Mounted on the upper face of the guide 30 inwardly of the wall 7 is a pair of spaced bearings 35 through which is journaled a spring actuated 35 shaft 36 having fixed thereon a dog 37 equipped with a subadjacently extending coin engaging section 38. The guide 30 is fashioned with a coin opening 39 adapted to register with the opening 33 when the slide is actuated inwardly and when 40 thus in registry the dog 37 serves to engage the coin and discharge the same downwardly through the opening 39 into a coin receptacle 40 secured to the wall 7. Pivotaly mounted on the upper face of the guide 30 adjacent the rear end thereof is a 45 bell crank lever 41, the outer end of which is connected by means of a spring 42 to the wall 7. The inner end of said bell crank lever is fashioned with a pin 43 operable within a slot 44 fashioned on one end of a magazine release arm 45. The 50 opposite end of said release arm is pivoted to the wall 7 as at 46. The magazine release arm 45, intermediate the ends thereof, is fashioned with a laterally extending section adapted to engage one of the stop members 27 and prevent rotation 55

- of the magazine in counterclockwise direction. Said laterally extending section 47 is maintained in the path of the members 27 through the medium of the spring 42 acting on the bell crank 5 lever 41. The arm of the bell crank lever 41 connected to the spring 42 between the ends thereof is provided with a downwardly extending coin engaging pin 48 extending into the slot 34 in the path of a coin.
- 10 Thus, when a coin is positioned in the opening 33 and the slide moved inwardly towards the opening 39 the coin will engage the pin 48, actuate the bell crank lever 41 which in turn causes the arm 45 to pivot away from the engaging stop 15 member 27 and permit rotation of the magazine. As the coin is discharged through the opening 39 through the action of the dog 31, the spring 42 causes the bell crank lever 41 to return to normal position and reposition the extended section 20 47 of the arm 45 in the path of the next stop member 27.
- Above the coin operated mechanism 29 the section 6 of the housing is fashioned with a transversely extending elongated opening 49 in 25 registry with one of the pockets 16, thus when a magazine is rotated as heretofore set forth the distance of one pocket the customer may reach through the opening 49 and extract the newspaper or periodical from the pocket.
- 30 Located above the opening 49 is a window 50 in registry with the pocket to be moved downwardly in registry with the opening 49 by the actuation of the coin operated mechanism 29 thereby permitting the customer to view the 35 pocket to determine whether a newspaper or the like is available before insertion of a coin. The upper end of the rear wall is provided with a door 51 whereby access is had to the interior of the housing to load the pockets of the magazine.
- 40 When the magazine is being loaded the latter is rotated in clockwise direction, the inclined faces of the members 27 serving to engage the laterally extending sections 47 of the arms 45 to operate

the bell crank lever and also to permit winding of the cable 18 about the drum 17. Thus when the pockets are loaded the device is set for vending operation as heretofore described.

What I claim is:

1. In a vending machine structure, a housing equipped with a dispensing opening in the front thereof, a magazine rotatably mounted in the housing and provided with side walls, radially extending partitions connecting said walls together and coacting with the latter to form a plurality of radially disposed pockets adapted for selective registry with said opening, said walls provided with arcuate shaped slots communicating with said pockets, shafts transversing said pockets and having ends extending through said slots, and springs mounted on the exterior side faces of said walls and having arms connected to the ends of said shafts for urging the latter towards said partitions whereby articles carried in said pockets are maintained clamped therein against said partitions by said shafts.

2. In a vending machine structure, a housing equipped with a dispensing opening in the front thereof, a cylindrical-shaped magazine rotatably mounted in the housing and provided with side walls, radially extending partitions connecting said walls together and coacting with the latter to form a plurality of radially disposed pockets adapted for selective registry with said opening, said walls provided with arcuate shaped slots adjacent the peripheries of said walls and communicating with said pockets, shafts transversing said pockets and having ends extending through said slots, rollers mounted on said shafts and rotatable relative to the latter, and springs mounted on the exterior side faces of said walls and having arms integrally connected to the ends of said shafts for urging the latter towards said partitions whereby articles carried in said pockets are maintained clamped therein against said partitions by said rollers.

ALBERT W. THORESON.
